UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

ANALYZING SYSTEM FOR MULTIPLEX FACSIMILE TRANSMISSION

Application filed May 3, 1929. Serial No. 360,067.

The present invention relates to a method and means for controlling light and is especially applicable and adapted to systems used in the transmission of pictures and the like for facsimile and television work. By 5 the term "pictures," of course, I mean to include the transmission of views, printed matter, checks, finger prints, photographs, financial statements, newspaper articles, advertisements, fashion plates, magazine articles, moving pictures, and the like, and in fact all types of subjects wherein a visual representation of the subject matter transmitted is to be reproduced at the receiving point.

More particularly, the invention is related 15 to a modification and further development of the light chopping disk arrangement set forth and claimed in my copending application, Serial No. 349,076, filed March 22, 20 1929, wherein I have disclosed a light chopping disk formed entirely of glass and provided with V-shaped notches extending about 25 the periphery in either a single track or in a plurality of concentric tracks depending, of course, upon whether the system is to be used in connection with a single channel transmission or multiplex transmission.

An object of the present invention is to provide a metallic disk for accomplishing the 30 light chopping action for the purpose of producing either a tone or a carrier frequency directly from the light beam reflected or projected back from the surface of a picture, in connection with opaque transmission, or 35 through a picture, in connection with film transmission.

Another object of my invention is to provide a disk member for producing a tone or carrier frequency which is relatively simple 40 in its construction and arrangement, and a disk which can be manufactured and produced at a minimum cost.

Still a further object of my invention is to provide a metallic disk arrangement for producing a tone or carrier frequency in which 45

the usual loss of approximately 50% of the available light is eliminated, and by means of which I can make use of substantially the entire amount of light available at all times.

Still other objects of my invention are to 50 provide in a manner to be hereinafter set forth, a light chopping disk arrangement which is simple in its construction and arrangement of parts, a disk which is light and easily rotated without the need of any 55 considerable amount of driving force, and a disk system which is readily applied to all types of existing apparatus using chopping disks for the purpose of producing tone or carrier frequencies.

Other and ancillary objects of my invention will at once suggest themselves and become apparent to those skilled in the art to which the invention relates by considering the following specification and claims in connection with the accompanying drawing, 65 wherein:

Fig. 1 conventionally illustrates an arrangement for impressing light chopped at different frequencies upon a pair of photoelectric members; and,

Fig. 2 illustrates a portion of one of my preferred types of light chopping disks, as applied to a two channel multiplex communication system, for example.

Referring now to the drawings forming a part of my present disclosure, and in particular to Fig. 1 thereof, light produced at a source 1 may be directed through a lens system 3 or the equivalent, such as a lens 75 or mirror disk or a spiral Nipkow disk, to a picture or television surface 5 from which the light beams may be reflected along the paths 7 and 9 respectively (considering the system as applied to a two channel multiplex 80 communication system). As the light beams 7 and 9 are reflected from the picture or television surface 5 they may be passed through a lens system 11 from which the individual beams are projected through a dia- 85

phragm member 13 provided with openings 15 and 17 therein. The diaphragm construction may be of the general type described and claimed in my copending application, Serial No. 321,821, filed November 26, 1928, wherein the diaphragm 13 may be adjusted along two planes at right angles to each other so that the size of the openings 15 and 17 therein, which should preferably be of a square formation, although this is not essential but merely for simplicity of illustration, may be made larger or smaller by adjusting the diaphragm so as to separate the reflected light from the picture or television surface 5 into two independent and distinct paths of light so as to scan more than a single unit area of the picture or television surface at the same time. As the light beam passing through the diaphragm has been split into 10 two independent and distinct paths of light 7' and 9', it may then be projected through a right angle prism 19 and deflected by the surface 21 thereof so as to follow a path through a focusing lens system 23 formed preferably 15 of a plurality of lenses 25 and 27. As the light beams leave the lens system 27, they are then preferably projected upon a disk surface 29 having a plurality of apertures, slots, or holes, 31 arranged in separate and 20 distinct paths A and B respectively, assuming the system to be a two channel multiplex communication system.

It will be seen by looking at the drawings that the two paths A and B formed by the 25 apertures 31 on the disk surface 29 are each of a different number of apertures. These paths may differ in the number of holes therein by any predetermined and chosen amount, as was disclosed in connection with the V-shaped grooves forming the plurality of separate and individual tracks in connection with the glass disk arrangement set forth and claimed in my above referred to copending application, Serial No. 349,076, filed March 40 22, 1929.

The surface of the disk 29 provided with the openings or apertures 31 therein is preferably formed from a light metal such as copper, for example, and may be accurately 45 laid out in a design laboratory where a disk may be drawn out on paper and most accurately divided into spaces, holes or apertures of equal size, so that the drawing may be placed in the hands of a photoengraver who may then make a photoengraving on the 50 copper plate forming the disk and thus make it as accurately as possible. The copper plate may then be cut down so that at the points 55 where the holes or apertures are intended to be placed in the disk, it will be very thin, and then by approximately coating the entire copper plate with wax and making a 60 photoengraving, the holes may be cut 65 through the disk by the usual photoengrav-

ing or etching process. Also, a disk may be formed by appropriately punching the holes therein. After the disk has thus been prepared and the apertures or holes 31 formed therein, the disk is polished and preferably 70 plated with a highly reflecting substance, such as, for example, chromium or silver.

It will now be seen that as the two light beams 7' and 9' are focused respectively upon the tracks A and B of the disk 29 and with 75 the disk rotating in the direction shown by the arrow thereon, rotational movement being derived from the supporting shaft 33 turned by means of a small electric motor or an air turbine, for example, the light projected along the paths 7' and 9' will, at pre-determined periods, pass through the holes or apertures 31 in the disk 29 and at other periods be reflected from the surface of the 80 disk between successive apertures.

As shown by Fig. 1, the light which passes through the disk 29 may be directed to a prism 35 and reflected from the face 37 thereof as two independent paths of light 7' and 9' to a photo cell 39, and, similarly, light reflected from the surface of the disk 29 along paths 7'' and 9'' may be projected upon a second photoelectric member 41. As was disclosed in my above named copending application, Serial No. 349,076, filed March 22, 95 1929, each of the photo cells 39 and 41 may be of the elongated type so that they may simultaneously be influenced by light passing through each of the separate and distinct paths A and B on the disk member 29. These 100 cells 39 and 41 may then be connected with a transmitting circuit in a manner similar to that disclosed in the last of my above named copending applications.

While I have described my invention particularly as being adapted to two channel multiplex communication systems, it will readily be seen that the invention is likewise applicable to a single channel communication system provided that only one path of 105 apertures or holes in the disk 29 is utilized, which might be produced, for example, by covering one of the diaphragm openings 15 or 17, or by making the disk 29 with only a single track of holes therein, or, in a similar manner, the system may be adapted to practically an infinite number of separate and distinct channels by providing a corresponding number of openings in the diaphragm 13 and making the disk 29 with a corresponding number of separate and distinct paths of holes 31 therein, in which case, 115 each of the separate paths on the disk will be composed of a different number of apertures, so that the rate of chopping the light for each of the separate and distinct paths differs. It is, however, preferable to have the number of holes in the disk 29 such that due to the 120 speed of rotation of the disk and the number 125 of apertures or holes in the disk 29, the number 130

of holes that the light is chopped at a rate corresponding to some predetermined harmonic of a basic chosen frequency upon which the entire system operates. This tends to provide a simplicity of operation. However, 5 it is not necessary that the number of holes be such that the light is chopped at any predetermined harmonic of any basic or chosen frequency but the chopping may be produced at any chosen and desired rate provided, of course, that suitable filters are located at the receiver used in conjunction with a multiplex system of the type herein disclosed so that the separate and individual 10 tones or carriers may be there distinguished.

Having thus described my invention, it will become apparent that various modifications may be made therein, and I, therefore, believe myself to be entitled to make and use each 15 of these modifications such as would become obvious to one skilled in the art to which the invention relates provided, of course, that such modifications fall fairly within the spirit and scope of the invention as set forth by the hereinafter appended claims.

Having now described my invention, what I claim and desire to secure by Letters Patent is the following:

1. In a picture transmitting system, a 20 source of light for illuminating a picture surface, means for separating the light reflected from the picture surface into a plurality of distinct and independent paths corresponding in number to the number of channels in 25 the communication system, a disk having arranged about the periphery thereof a plurality of independent and distinct apertures, means for successively and alternately projecting light through the apertures of the 30 disk and reflecting the light from the space between successive apertures in the disk, and a photo cell positioned in the path of each of said projected and reflected paths of light.

2. In a multiplex communication system, 35 a light chopping disk having a plurality of concentrically arranged apertures extending about the periphery thereof and the space between said apertures being highly reflecting, means for projecting light as a plurality 40 of light beams against each independent path of apertures on said disk, and photoelectric means positioned in front and behind said disk, and means provided by rotating said disk for alternately and successively 45 subjecting the photoelectric elements to direct and reflected light projected upon said rotating disk.

3. In a picture transmitting system, a 50 source of light for illuminating a picture surface, means for reflecting said light from the picture surface, a disk having arranged about the periphery thereof a plurality of independent and distinct apertures, means 55 for successively and alternately projecting said reflected light through the said aper-

tures of the disk and reflecting the light from the space between successive apertures in the disk, and a photo cell positioned in the path of each of said projected and reflected paths of light.

4. In a multiplex communication system, 70 a light chopping disk having a plurality of concentrically arranged apertures extending about the periphery thereof and a highly reflecting surface in the space between said apertures, means for projecting light as a plurality of varying intensity light beams against each independent path of apertures on said disk, photoelectric means positioned in front and behind said disk, and means 75 provided by rotating said disk for alternately and successively subjecting the photoelectric elements to direct and reflected light projected upon said rotating disk.

5. In a picture transmitting system, a 80 source of light for illuminating a picture surface, means for separating the light reflected from the picture surface into a plurality of distinct and independent paths corresponding in number to the number of channels in 85 the communication system, a disk having arranged concentrically about the periphery thereof a plurality of independent and distinct rows of apertures, means for successively and alternately projecting light 90 through the said apertures in said disk and reflecting the light from the space between successive apertures in said disk, and a photo cell positioned in the path of each of said projected and reflected paths of light.

6. In a picture transmitting system, a 95 source of light for illuminating a picture surface, means for separating the light reflected from the picture surface into a plurality of distinct and independent paths corresponding in number to the number of channels in the communication system, a rotating disk provided with a plurality of rows of independent and distinct apertures arranged in concentric paths about the periphery thereof, means for sequentially projecting said plurality of light beams through separate rows of said apertures of the disk and reflecting the light beams from the space between the successive apertures in the disk, and a photo cell positioned in the path of each of said projected and reflected paths of light.

7. A light chopping disk having a concentrically arranged row of apertures adapted to pass light, and a light reflecting material on the disk surface between said apertures.

8. A light chopping disk having a plurality of concentrically arranged rows of apertures each adapted to pass light, and a light reflecting material on the disk surface between successive apertures of each of the rows.

9. In a picture transmitting system, a 120 source of light for illuminating the picture

surface, a light chopping disk having a concentric row of apertures each adapted to pass light arranged about the periphery thereof and a light reflecting material on the disk surface between said apertures, light translating elements arranged on each side of said disk, and means provided by the rotation of said disk for alternately and successively directing the light reflected from the picture surface through and from the surface of said disk so as to alternately influence each of said light translating elements.
